UNITED STATES PATENT OFFICE.

WILLIAM BLIESNER, OF EAST ST. LOUIS, ILLINOIS.

VAPOR-BURNER.

SPECIFICATION forming part of Letters Patent No. 334,737, dated January 26, 1886.

Application filed September 20, 1884. Serial No. 143,582. (No model.)

To all whom it may concern:

Be it known that I, WILLIAM BLIESNER, of East St. Louis, Illinois, have made a new and useful Improvement in Vapor - Burners, of which the following is a full, clear, and exact description, reference being had to the annexed drawings, making part of this specification, in which—

Figure 1 is a side elevation of a vapor-burner having the improvement, a portion of the construction in the vicinity of the combining-chamber pivot being in section; Fig. 2, a view taken at right angles to that of Fig. 1, and being an elevation of the upper portion 15 of the burner, the supply-pipe not being shown, and the large combining-chamber being above the vapor-orifice in position to receive the vapor therefrom as in use; Fig. 3, a view similar to that of Fig. 2, but showing 20 the movable part of the top of the burner swung aside to bring the small combining-chamber into position above the vapor-orifice to receive the vapor, the small combining-chamber being shown in vertical section; Figs. 25 4 and 5, top views of the parts shown in Figs. 2 and 3, respectively, the perforated cap being removed; and Fig. 6, a vertical section of that portion of the supply-pipe in which the packing device is contained.

30 The same letters of reference denote the same parts.

It is frequently desirable to diminish the flame of a vapor-burner. To this end it has been the practice to reduce the supply of vapor by partially closing the vapor-orifice. The vapor thus diminished in quantity is sometimes insufficient for the combining-chamber and the flame goes out.

To prevent this difficulty is the object of the 40 present invention, which consists, mainly, in providing the burner with two combining-chambers in place of a single combining-chamber, the two combining-chambers being attached to a swinging plate, substantially as follows:

A, Fig. 1, represents a vapor-burner of the customary form, saving as modified by the present improvement. B represents the pipe through which the fluid is supplied to the 50 burner. C represents the retort. D represents the orifice from which the vapor escapes

into the combining-chamber. E represents the valve-stem, and F represents the handle for working the valve-stem, all of which parts are used in the customary manner, and are of 55 the customary form, with the exception of the supply-pipe, which is modified to suit the improved packing device, as hereinafter explained.

G represents the larger combining-chamber. It is of the ordinary shape, and when in use is used in the usual manner. Instead, however, of being fixed in its position, it is pivoted at g to the fixed portion of the burner, so that it can be swung, and so that the tube 60 g', which constitutes the lower part of the combining-chamber, can either be brought directly over the orifice D, so that the vapor can pass into the combining-chamber G, as in Figs. 1, 2, 4, or to one side thereof, so that the vapor 65 cannot pass into the combining-chamber G, as in Figs. 3, 5.

H represents the smaller combining-chamber. It is smaller than the chamber G, and is adapted to receive the vapor from the orifice 70 D when the vapor-supply is diminished, and it is perforated at h, the perforations h serving the same purpose in the chamber H that the perforations g' serve in the chamber G. The chamber H, similarly to the chamber G, can 75 be shifted to bring it either in coincidence with the orifice D, so that the vapor can pass into it, as in Figs. 3, 5, or out of coincidence with the orifice, as in Figs. 1, 2, 4. To this end, as the most convenient method therefor, the chamber 80 H is attached to the plate g' of the chamber G. This plate is the part which supports the cap g', and is pivoted at g, and it, in effect, is a bracket which carries both of the combining-chambers. When it is swung one way upon the pivot g, 85 one of the combining-chambers is brought into coincidence with the vapor-orifice D, and when it is swung the opposite way the other of the combining-chambers is brought into coincidence with the vapor-orifice.

The chamber H and the retort are so relatively arranged that when the chamber H is being used the flame from some of the perforations h is adapted to heat the retort.

When a strong heat is desired, the large combining-chamber is brought over the orifice D and the burner-valve is opened, and when a

mild heat is desired the small combining-chamber is brought over the orifice D and the burner-valve is partially closed. Owing to the small capacity of the chamber H and its relation to the orifice D, only that amount of air which is requisite for the diminished vapor-supply enters the chamber H, and by reason of the flame from the chamber H being adapted to heat the retort, that part is sufficiently 10 warmed to effect the desired vaporization of the gasoline, and the flame of the smaller combining-chamber does not go out. The chamber H at its lower end is brought sufficiently near the orifice D, and is otherwise suitably shaped 15 to prevent too much air entering the chamber.

The improvement further relates to the regulation of the flow of fluid to the burners.

I, Fig. 6, represents a regulator in the shape of a ball, whose function is to regulate the flow 20 of gasoline from the supply-pipe as it passes the point *i* toward the retort. This ball should be nicely adjusted as to its weight, so as to of

fer sufficient resistance to the hydrostatic pressure upon it to prevent too large a flow of gasoline into the retort. If the ball is thus properly adjusted, it will be lifted up by the pressure and held in suspension by the flow of the gasoline, and so, by regulating the flow, secure uninterrupted evenness to the flame, while, owing to its position and relation to the supply-pipe at the point *i*, it must necessarily act as a check against any counterpressure. 25 30

I claim—

A vapor-burner having the ordinary valve and provided with the plate g^3 , pivoted at g , 35 and carrying the combining-chambers G and H, substantially as and for the purpose described.

Witness my hand.

WILLIAM BLIESNER.
